UNITED STATES PATENT OFFICE.

WILLIAM H. BUCKINGHAM, OF MAYFIELD, PENNSYLVANIA, ASSIGNOR OF FORTY-NINE ONE-HUNDREDTHS TO G. FRANK COUCH, OF CARBONDALE, PENNSYLVANIA.

INTERCHANGEABLE SANDER.

Application filed March 1, 1924. Serial No. 696,368.

To all whom it may concern:

Be it known that I, WILLIAM H. BUCKINGHAM, a citizen of the United States, residing at Mayfield, in the county of Lackawanna and State of Pennsylvania, have invented a new and useful Interchangeable Sander, of which the following is a specification.

My invention relates to sanders for wheeled vehicles.

10 Although my improvements are applicable to any type of vehicles—such as steam or electric locomotives, I will describe it (for purposes illustrative of its use) as applied to a steam locomotive.

15 All locomotives carry a sand box generally in a dome on the top of the boiler from which a pipe is connected and leads down to a point above both rails immediately above and in front of or between the drivers on each side of the locomotive. Most all 20 of these sanding devices are provided with suitable devices for inducing and controlling the flow of sand to the tracks.

25 The sanders at present in use are provided with steam or air jetting devices for atomizing or breaking up the packing of sand and furnishing to the track the desired quantity of sand to provide the approximate degree of grip of the driving wheels upon 30 the road bed.

This blowing of the sand in the sander, acts, through the cutting quality of the sand, to wear out the walls of the inner shell of the sander. This serious objection I have 35 obviated and I have produced a sander which will last twice as long as those now in use. Furthermore my improved sander is capable of more flexible installation in adapting it to various types of wheeled vehicles at present in use, owing to the fact that it can be 40 installed either side up.

The drawings which serve here to exemplify one way of carrying out my invention are—

45 Figure 1 a central vertical sectional view of my sander.

Figure 2, an end view of the same.

In the drawings—1 represents the body of the sander. 2 is the diagonal main passage or chamber.

50 3 is the receiving passage to the upper end 4, from which a pipe leads to the sand dome of the locomotive above, and is connected with the lower end of the main chamber 2.

55 5 is a vertical passage which leads into

the upper end of the chamber 2 and connects with the pipe which leads to a point directly above the railroad track.

6 is the jet nozzle connecting with a fluid pipe 7 leading to a source of fluid supply 60 (such as air or steam) under pressure for blowing or atomizing the sand in the sander and discharging it into the discharge passage 5 even if the sand in the sander has packed 65 or is lumpy.

8 is a removable plug which carries the jet nozzle 6 at the lower end of the chamber 2.

9 is a plug similar to the plug 8 closing the upper end of chamber 2 and interchangeable therewith. A convenient diameter for these plugs is an inch and a quarter. Laterally of each passage 3 and 5 I insert removable plugs 10 of say three quarters of an inch, 70 which are interchangeable and which serve 75 as clean outs.

My sander when installed receives the sand from the dome into passage 3 and chamber 2. Upon the opening of the fluid jet 6 the sand is disintegrated and sprayed 80 upwardly into the top of the chamber 2 and falls lightly and evenly down through passage 5 to the track.

These sanders as heretofore made do not give very long service, because the sand 85 blasts induced therein wear out the interior of the sander. To prolong the life of the sander I have made it reversible. It will be noted that the sander may be reversed or 90 simply turned end for end, and the interchangeable plugs 8 and 9 reversed, whereupon the sander operates precisely as it did before.

A convenient size for the pipes that lead 95 into passage 3 and out of passage 5 is one inch which is standard for this service.

In order to prevent the possibility of any clogging up of the discharge passages 3 or 5, I may introduce an auxiliary jet 11 or 12, or both, into these passages. For this purpose the fluid pipe 7 may be tapped at 13 and pipes 14 and 15 brought into communication with the jets 11 and 12.

As a matter of practice it will probably be preferable to use simply the auxiliary system 10, 12, and 14 in the passage 5 leading from the sander to the track, the corresponding opening in passage 3 shown in the drawing as being occupied by bushing plug 10 being plugged with a usual plug similar 105 110

to plug 9 and the jet 11 and pipe 15 removed.

In reversing the device the auxiliary jet is correspondingly changed.

5 I claim—

An interchangeable reversible sand trap comprising a housing having a diagonal pas-

sage therethrough, vertical passages leading from each end of the diagonal passage, and interchangeable plugs at each end of the 10 diagonal passage one of which contains a jet nozzle whereby the sander may be reversibly installed.

WILLIAM H. BUCKINGHAM.
